UNITED STATES PATENT OFFICE.

FERDINAND J. SPANG, OF BUTLER, PENNSYLVANIA.

THREAD PROTECTOR.

Application filed August 13, 1924. Serial No. 732,824.

This invention relates to thread protectors such as are used to protect the threads of various implements and articles when in transit or while not in use.

It is now considered good practice to use protectors for covering the threads of various articles such as tools for use in well drilling, pipes, stems and joints, etc. and an object of this invention is to produce an improved form of protecting device capable of being incorporated in both male and female protectors and especially those adapted for the boxes and pins of well drilling tools.

These boxes—so called—are threaded conical chambers formed in the ends of the joint members and the pins—so called—are threaded conical projections on such members. The pins and boxes are adapted to cooperate in securing tool elements together.

It is desirable to prevent moisture from gaining access to the threads and it is also desirable to be able to coat them with oil or grease and hold the same in place.

Another object of this invention is to produce both male and female protectors for the threaded boxes and pins of well drilling tools or tool joints that will not only protect the threads thereof, but will keep moisture out and hold oil or grease in place thereon.

A further object is to produce protectors for the pins and boxes of well drilling tool elements or joints of material that is stiff enough to serve as a real protection yet is so much softer than the metal of which the joints are formed that collision of the protectors with external objects will not in any manner injure the protected threads.

These, as well as other objects which will be apparent to those skilled in the art to which this invention relates, I attain by means of the devices described in the specification and illustrated in the drawings accompanying and forming part of this application.

In the drawings—

Figure 1 is a side elevation of a tool having a threaded pin, showing in section one embodiment of this invention applied thereto, Fig. 2 is a side elevation of the form of this invention shown in Fig. 1, Fig. 3 is an end elevation and Fig. 4 is a longitudinal section thereof, Fig. 5 is a view of a tool provided with a box joint showing in section another form of this invention applied thereto, Fig. 6 is a section of the device

shown in Fig. 5 and Fig. 7 is an end elevation thereof.

Figs. 1 to 4 illustrate an embodiment of this invention which is particularly adapted for use with a threaded pin, rod or the like such as the pin 10 of a well drilling tool 11. This form includes an annular body portion 12 made of flexible or elastic material such as rubber and which, in the present instant, is tapered throughout its length to conform to the tapered pin 10. The narrow end of the body 12 is provided with several threads 13 adapted to engage the threads at the outer end of the pin. Ridges 14 are formed on the outer face of the annular body 12 so as to provide a gripping surface for use in threading the protector on and off the pin 10. The other end of the annular member is provided with a flange 15 which has a slightly dished or concaved face 16, see Fig. 4, so that when the protector is in position on the pin 10, as shown in Fig. 1, the flange 15 will be slightly bent or flexed by contact with the shoulder 17 at the base of the pin 10 when the protector is applied so as to form an air tight joint between the thread protector and the shoulder 17. A chamber 18 is provided between the threads 13 and the flange 15 which may conveniently be filled with grease to prevent corrosion of the threads.

In Figs. 5 to 7 there is shown another embodiment of the invention which is particularly adapted to protect the "box" 20 of a well drilling tool 21. This form includes an annular member 22 having external threads 23 at one end for engaging the internal threads of the box 20. The other end is provided with a flange 24 which is formed similarly to the flange 15 so as to have an inclined bottom face 25. Ribs 26 are preferably formed within the annular member for use in threading and unthreading and the inner end of the threaded portion is closed by wall 26^a, with which the ribs 26 connect. When the member is threaded into the box 20 the face 25 of the flange 24 engages the end 27 of the tool and when the protector is in applied position, flange 24 is flexed and thus caused to form an airtight joint with end 27 of the tool.

The protector is preferably made from rubber or rubber composition which will not itself injure the threads to which it may be applied and is sufficiently flexible and elastic

to insure a tight joint between the deflected flange and the article at one end and between the threads of the protector and the threads of the article at the other end.

5 While I have described specific forms of this invention I do not wish to be limited to the details thereof but what I claim as new and desire to secure by Letters Patent is:

10 1. A thread protector comprising a tapered hollow body open at both ends, a resilient internally threaded portion disposed adjacent the smaller end of said body and an outwardly extending dished resilient flange disposed on the larger end, the body 15 of the said protector having an internal diameter greater than the internal diameter of the said threads.

20 2. The combination with a tapered threaded annular member having a shank portion at its larger end, of a thread protector comprising a hollow tapered cylindrical body open at both ends and having a resilient internally threaded portion at the smaller end of said body, the internal diameter of 25 the said resilient threads being substantially the same as the external diameter of the

smaller end of the tapered threaded member, and a dished resilient flange disposed on the larger end of the body and extending outwardly therefrom, the internal diameter 30 of the larger end of the thread protector being substantially the same as the external diameter of the shank portion on the threaded member, the main body portion of the thread protector having internal diameters greater than the corresponding external diameters of the said threaded annular member. 35

3. A thread protector including a body portion having a thread-engaging section 40 located adjacent one end thereof, and an outwardly-extending annular flange of substantially greater diameter than said body portion and provided with an annular article-engaging face positioned at an oblique angle 45 to the axis of the protector and located at the other end.

In testimony whereof, I have hereunto subscribed my name this 12th day of August, 1924.

FERDINAND J. SPANG.
